[57] CLAIM

The ornamental design for a bag dispensing carton, as shown and described.

DESCRIPTION

FIG. 1 is a perspective view of a bag dispensing carton showing our new design;

FIG. 2 is a side view;

FIG. 3 is an end view;

FIG. 4 is another end view;

FIG. 5 is a bottom view; and

FIG. 6 is a perspective view showing the end flap folded back and showing bags in broken lines for the purpose of illustrating environmental use only.

FIG. 1

FIG. 2

FIG. 3

FIG. 4

FIG. 5

FIG. 6
